TOOL ATTACHMENT

Arthur Scott, Cleveland, Ohio, assignor to The Cleveland Pneumatic Tool Company, Cleveland, Ohio, a corporation of Ohio

Application September 15, 1930, Serial No. 481,875

9 Claims. (Cl. 94—48)

This invention relates to a tool for use in combination with a pneumatic or fluid operated hammer. It has to do more particularly with a tamping tool used for packing loose materials such as gravel, cinders, or sand, although it is not necessarily limited thereto.

Tamping tools now used with fluid operated hammers, due to the reciprocating action thereof, will throw sand and other abrasive material into intimate relation with the stuffing box and the surface of the ram, thus causing a deleterious effect upon the moving parts. This is due to the fact that the configuration of the tool causes the sand to be thrown against the ram in its reciprocating motion, particularly is this true when the tool is in the form of a truncated cone, convergent with the ram, forming a focal point adjacent the stuffing box, into which the entrained abrasive is thrown. Moreover, the means customarily used in attaching the tool to the end of the ram is such that the vibratory action of the ram is effective in creating fractures in the tool. The frequent replacement of tools is a costly and undesirable feature of the tools in present use.

One of the objects of my invention is to provide a tool of such configuration that any material carried by the tool in its vibratory action will be thrown radially outward from the surface of the tool and remote from the reciprocating ram.

Another object of my invention is to construct a tamping tool which is capable of resisting the deleterious effects of the vibration to which it is subjected and to provide a structure which is insusceptible to fracture.

Another object of my invention is to construct a tamping tool which is sturdy of structure, economic of manufacture and insusceptible to undue deterioration.

Further objects will be apparent from the following detail description wherein similar characters of reference designate corresponding parts and wherein:

Fig. 1 is an elevation partly in section of a pneumatic hammer with the preferred embodiment of my tool attached thereto.

Fig. 2 is a plan view of my tool.

Fig. 3 is a sectional view taken on a plane indicated by the line 3—3 of Fig. 2 showing the means which I preferably use for securing my tool to the reciprocating ram.

With reference to the drawing I have shown in Fig. 1 a pneumatic hammer of the usual type, comprising a cylinder 10 and a stuffing box 11,

shown in detail, integrally constructed in the lower end thereof. A ram 12 is adapted to reciprocate within the cylinder 10 and has the tamping tool 13 secured to the lower end thereof as at 13'. The means which I preferably use will be, hereinafter, referred to more in detail.

The tamping tool 13 is hollow, and has a body portion 14 of a frusto-spheroidal form having an inwardly tapering surface as at 15. It is well known that in using a tamping tool the head will become imbedded into the loose material at the end of each outward stroke. For this reason, I have constructed my tool with a spheroidal surface, in order that upon the return stroke any material lying adjacent such surface will be thrown radially outward as shown in Fig. 1, instead of against the reciprocating ram.

With reference to Fig. 3, I have shown the construction which I preferably use for receiving the outer end of the ram 12 as comprising a cylindrical insert 16 having the outwardly extending flange 17 formed integrally therewith. On the opposing end thereof I have formed the shoulder 19 by substantially reducing the diameter of the cylindrical insert 16. The purpose of this construction is to form the surfaces 17' and 19' which abut against bosses 20 and 20' formed integrally with the body portion 14 of the tamping tool. The insert 16 has a tapered cylindrical aperture 21 of complementary configuration with the outermost end 22 of the ram 12 and is adapted to receive such ram and secure it therein.

The upper and lower walls of the hollow tamping tool 13 are centrally bored as at 23 and 18 and are adapted to receive the insert 16 which is securely fixed in the body portion in spaced relation with the walls thereof except for its end portions which are welded as shown to surfaces 24 and 25.

It is possible in the above described construction to form the insert 16 of a somewhat softer steel than the body portion 14. The advantage of this construction is that since the insert is located in spaced relation with the side walls of the tamping tool, it will be capable of distortion but not fracture and of receiving the repeated thrust of the ram without transmitting other than a downward force on the bosses 20 and 20' of the body portion.

From the foregoing description it will be seen that the advantageous features of my invention reside in the fact that I have provided a tamping tool of such configuration that upon the return stroke of the ram any material cover-

ing the faces of the tool will be thrown outwardly therefrom, and that the construction of the tamping tool adequately provides for the reception of the downward blows exerted upon the body portion of my tamping tool, and insures against breakage or fracture.

I claim:

1. A butt for backfill tampers comprising a body portion formed with a striking face, a frusto-spheroidal hood extending upwardly from said striking face, and a stem extending from the upper portion of said hood to said striking face formed with a piston rod receiving tapered socket.
2. A butt for backfill tampers comprising a circular body portion formed with a striking surface, a convex hood extending upwardly from said striking surface, and a piston rod receiving stem connecting the upper portion of said hood with the central portion of said striking surface.
3. A butt for backfill tampers comprising a circular body portion formed with a striking surface, a convex hood extending upwardly from the marginal edge of said striking surface, and a piston rod receiving stem within said hood secured to the upper portion thereof and the central portion of said striking face.
4. A butt for backfill tampers comprising a hollow body portion the forward end wall thereof of constituting a striking face, a convex hood extending from said striking face, and piston rod receiving means comprising an insert formed with a shoulder engageable with the upper portion of said hood for limiting the movement of said insert toward said striking face.
5. A butt for backfill tampers comprising a hollow body portion with the forward end wall

thereof constituting a striking face, a convex hood extending from said striking face, and piston rod receiving means comprising an insert centrally located within said hood formed with a shoulder engageable with said forward end wall.

6. A butt for backfill tampers and the like comprising a hollow body formed with a striking face, and a piston rod receiving member within said body located in spaced relation with the wall thereof except for its end portions rigidly secured to the upper and lower wall thereof.

7. A butt for backfill tampers and the like comprising a body portion formed with a hollow core, a stem formed with a piston receiving socket, said stem extending through said hollow core from the upper to the lower wall of said body portion, said socket being closed from said hollow core.

8. A butt for backfill tampers and the like comprising a hollow body, the lower wall thereof being formed with a substantially flat surface constituting the striking face of the butt, a stanchion within said body extending from said lower wall to the upper wall of said body in spaced relation with the side wall thereof, and a piston receiving socket formed within said stanchion.

9. A butt for backfill tampers and the like comprising a body portion formed with a hollow core entirely closed from the exterior of said body portion, and a central portion extending into said hollow core formed with a piston rod receiving means leading to the exterior of said body portion.

ARTHUR SCOTT.
